UNITED STATES PATENT OFFICE

145,090

DESIGN FOR A WOODEN SLIPPER OR SIMILAR ARTICLE

Ken Y. Kono, Riverside, Calif.

Application February 11, 1946, Serial No. 126,448

Term of patent 7 years

(Cl. D7—7)

To all whom it may concern:

Be it known that I, Ken Y. Kono, a citizen of the United States, residing in the city of Riverside, in the county of Riverside and State of California, have invented a new, original, and ornamental Design for a Wooden Slipper or Similar Article, of which the following is a specification, reference being had to the accompanying drawing, forming a part thereof.

I claim:

The ornamental design for a wooden slipper or similar article, as shown:

KEN Y. KONO.
